UNITED STATES PATENT OFFICE.

ETHAN I. DODDS, OF CENTRAL VALLEY, NEW YORK, ASSIGNOR TO KERNER MANUFACTURING COMPANY, OF PITTSBURGH, PENNSYLVANIA, A CORPORATION OF PENNSYLVANIA.

POWER-OPERATED HAND PLANER OR SMOOTHING TOOL.

1,090,602.

Specification of Letters Patent.

Patented Mar. 17, 1914.

Application filed January 22, 1913. Serial No. 743,537.

To all whom it may concern:

Be it known that I, ETHAN I. DODDS, a citizen of the United States, and resident of Central Valley, Orange county, New York, have invented a new and useful Improvement in Power-Operated Hand Planers or Smoothers, of which the following is a full, clear, and exact description, reference being had to the accompanying drawings, forming 10 part of this specification, in which—

Figure 1 is an end view of a power planer or smoother embodying my invention; Fig. 2 is a front elevation of the same; Fig. 3 is a transverse vertical section; Fig. 4 is a top plan view; Fig. 5 is a horizontal vertical section; Fig. 6 is a view similar to Fig. 3, but the section being taken on a different line; Fig. 7 is a rear elevation with the handle portion cut away; and Fig. 8 is an end view, 20 looking at the opposite end from Fig. 1.

My invention has relation to power-operated hand tools, such as planers or smoothers, and is designed to provide a simple, efficient and convenient tool of this 25 character driven by electric power.

The nature of my invention will be best understood by reference to the accompanying drawing, in which I have shown the preferred embodiment thereof, and which will 30 now be described, it being premised, however, that various changes can be made in the details of construction and arrangement of the parts without departing from the spirit and scope of my invention as defined 35 in the appended claims.

In these drawings, the numeral 2 designates the handle of the tool, the portion 2^a thereof being shaped to form a hand grasp. The lower plane surface 3 of the handle 40 forms a guiding surface, which is moved along the floor or other surface to be planed or smoothed by the tool. This handle portion has a forward upwardly arched projection 4 to receive the tool casing 5. This 45 tool casing is arranged transversely, and is of general cylindrical form, comprising a body portion which is partially cut away as best shown at 6 in Figs. 3 and 6, and detachable end heads 7. The body portion of 50 the cylinder is provided with bearings 8 for the intermediate portion of an armature shaft 9; and each end head is provided with a suitable end bearing 10 for said shaft. Secured to each end portion of the shaft with-

in the casing is an armature 11 of an electric motor, whose field magnets 12 are carried by the casing. Each of the cap members 7 is provided with suitable supports 13 for the commutator brushes 14 of the motors.

15 is a tool shaft, which is journaled in 55 the cut-away portion of the casing, in suitable bearings 16. This shaft is shown as having a plurality of helically arranged cutting plates 17, although it may carry any suitable form of smoothing, planing or dressing tool. At each end of the tool a gear wheel 18 is fixed to this shaft, these gear 60 wheels meshing respectively with the pinions 19 and 20 on the armature shaft.

21 designates a guard for the tool, said 65 guard being pivoted on the tool shaft 15 between the two gear wheels 18. This guard is shown as connected by a link 22 with a crank arm 23 on one end of a rock shaft 24, which is journaled in the handle 70 portion of the tool. This shaft 24 also carries a contact portion 25, which co-operates with the relatively fixed contact members 26 for controlling the circuit of the electric 75 motors, these fixed contacts being carried by 80 the terminal plates 27. Also secured to the shaft 24 is a projecting thumb piece 28, in convenient position to be engaged by the thumb when the handle portion is grasped by the hand. The arrangement of the parts 85 thus described is such that when the thumb piece 28 is pressed downwardly by the thumb, the shaft 24 is rocked in its bearings to move the contact member 25 into position to close the motor circuits, and at the same 90 time, through the medium of the crank 23 and link 22, to move the pivoted guard 21 from the position shown in full lines in the drawings to the position shown in dotted lines in Fig. 6, thereby exposing the cutting 95 edges of the tool. The shaft 24 is normally held in, and is returned to, a position in which the motor circuit is opened by means of a spring 28^a (Fig. 1) attached to one end of said shaft. As soon as the thumb piece 100 is released, this spring will cause it to immediately open the motor circuits.

The tool casing is adjustably suspended from the overhanging portion 4 in a manner to permit it to be readily moved vertically to vary the depth of cut of the tool, this depth of cut being regulated by the distance to which the cutting edges of the tool

project below the guiding surface 3. In the arrangement shown, I have shown the tool casing as suspended by means of the adjustable screw 29, which also forms means whereby the entire tool casing and tool can be raised and lowered, being guided in this movement by the pins or screws 30 seated in the overhanging portion 4 and engaging apertures 31 in the casing. Fig. 3 shows the tool casing and tool adjusted to its highest position, while Fig. 6 shows a lower adjustment.

The advantages of my invention will be readily appreciated. The tool can be readily connected by flexible conductors with a convenient source of electric current; it is easily portable, and can be readily manipulated with respect to the surfaces to be operated upon; it can be easily and quickly adjusted so as to give any desired depth of cut; and any desired amount of power can be obtained, according to the capacity of the motors used. The manner of applying power to each end of the armature shaft and gearing this shaft to each end portion of the tool shaft provides an effective drive for the tool shaft whereby an even steady cutting action is insured.

Instead of a cutting tool, I may employ a suitable form of rotary grinding tool. The device is thus capable of a wide variety of uses.

I claim:—

1. A portable tool of the character described, comprising a central handle portion, a combined motor and tool-supporting frame suspended from the handle portion and extending laterally to each side thereof, a tool shaft journaled in the central portion of said frame, and a motor mounted at each end portion of the frame and geared to the tool shaft, substantially as described.

2. A portable tool of the character described, comprising a central handle member having a forwardly projecting upwardly arched portion, a combined tool and motor-supporting frame adjustably sus-

pended from and within said arched portion, said frame having a tool shaft journaled longitudinally at the central portion 50 thereof, and a motor supported by each end portion of the frame and having a driving connection with said tool shaft, substantially as described.

3. A portable tool of the character described, comprising a handle member having a bottom guiding surface and also having a forward extension, a combined tool and motor-supporting frame, a casing adjustably suspended from said extension and 60 movable vertically with reference to said guiding surface, a tool shaft journaled in the central portion of the frame and casing, and a motor mounted within each end portion of said frame and casing and having a 65 driving connection with the tool shaft, substantially as described.

4. A portable tool of the character described, comprising a central handle member, a combined motor and tool-supporting 70 frame carried by said handle member and extending laterally to each side thereof, a motor shaft journaled longitudinally in said frame, a motor member connected to each end portion of said shaft, and a tool shaft 75 also journaled in said frame and having a plurality of driving connections with the motor shaft, substantially as described.

5. A portable tool of the character described, comprising a handle portion, a tool 80 carrier supported thereby and having a rotary tool, and motors for driving said tool, a device on the handle portion for controlling the said motors, a thumb piece for actuating the said device, a movable guard for 85 the tool, and an actuating connection between the thumb piece and the guard; substantially as described.

In testimony whereof, I have hereunto set my hand.

ETHAN I. DODDS.
